(57) **CLAIM**

The ornamental design for a mobile phone display screen, as shown and described.

DESCRIPTION

FIG. 1 is a top, front, left side perspective view of a mobile phone display screen, showing our new design;

FIG. 2 is a bottom, rear, right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion labeled **9** in FIG. 2; and,

FIG. 10 is an enlarged view of a portion labeled **10** in FIG. 2.

The dash dot dash lines in FIG. 2, FIG. 9 and FIG. 10 define the enlarged views and form no part of the claim.
